United States Patent Office

Des. 229,700

Patented Dec. 25, 1973

229,700

DATA RECORDER

Thomas L. Richardson, Horsham, Bruno Kersten, Springfield, and Charles T. Johnson, Philadelphia, Pa., assignors to Decision Data Computer Corporation, Warminster, Pa.

Filed Sept. 27, 1971, Ser. No. 184,331

Term of patent 14 years

Int. Cl. D14—02

U.S. Cl. D26—5 C

FIG. 1

Des. 229,700

PAGE 2

FIG.2

FIG. 4

FIG. 3

FIG. 5

FIG. 6

FIG. 7

FIG. 1 is a perspective view of a data recorder embodying our new design;

FIG. 2 is a perspective view of a modified form of the data recorder shown in FIG. 1;

FIG. 3 is a front elevational view of FIG. 2;

FIG. 4 is a top plan view of FIG. 2;

FIG. 5 is a rear elevational view of FIG. 2;

FIG. 6 is a left side elevational view of FIG. 2; and

FIG. 7 is a right side elevational view of FIG. 1.

The broken line representation of support structure in FIG. 1 is for purposes of illustration only.

We claim:

The ornamental design for a data recorder, as shown and described.
